DESIGN FOR AN AIR CONDITIONING CABINET OR SIMILAR ARTICLE

Ralph E. Kruck, Springfield, Mass., assignor to Westinghouse Electric & Manufacturing Company, a corporation of Pennsylvania

Application April 1, 1937, Serial No. 68,511

Term of patent 7 years

To all whom it may concern:

Be it known that I, Ralph E. Kruck, a citizen of the United States, residing at Springfield, in the county of Hampden and State of Massachusetts, have invented a new, original, and ornamental Design for an Air Conditioning Cabinet or Similar Article, of which the following is a specification, reference being had to the accompanying drawing forming a part thereof.

The figure is a perspective view of an air con-

ditioning cabinet or similar article, showing my new design.

The right hand side of the cabinet is like the left hand side shown on the drawing.

I claim:

The ornamental design for an air conditioning cabinet or similar article, substantially as shown and described.

RALPH E. KRUCK.
